ALBUM

Albert A. Ainsworth, Ossining, N. Y.

Application February 17, 1936, Serial No. 64,289

15 Claims. (Cl. 129—20)

This invention relates to picture albums or other similar record books, filing folders, display cards, easels, and the like, and to a novel envelope which may be employed in progressively adding 5 to the record contained in such books, etc.

The invention is not limited in utility to the ordinary picture album but may be used in compiling other records, such as army records, employees records, finger print records, etc. either 10 in book, folder or easel form. For purposes of illustration, however, the invention will be described as applied for use in an ordinary picture album.

In accordance with one feature of the present 15 invention provision is made of an envelope having a gummed flap divided from the envelope body by a fold line, and of a series of tabs punched from the body of the flap and having their bases preferably but not necessarily coincident with the fold line so that the tabs may 20 be folded out of the plane of the envelope body independently of the remaining portion of the flap.

In utilizing such an envelope in a photograph 25 album or other book or folder or when mounted upon any comparatively stiff backing such as an easel or the like, a photograph may be first placed over the main body of the gummed flap but beneath the tabs, and adhesively united to the tabs by the adhesive which is present on 30 the tabs. The free margin of the flap is then pasted in the album, book, folder, or easel, the body of the envelope extending downward from the flap which has been attached. The independent hinge formed by the tabs and connected 35 to the picture may be folded down so that the picture overlies the envelope. The envelope is used as a receptacle or repository for the negative from which the picture has been made, and the 40 face of the envelope may have identifying or descriptive data written upon it. The envelope body is desirably provided with a printed form on its exposed face for receiving such descriptive data as is customarily desired.

Each photograph and envelope attached in the 45 book or folder or upon any comparatively stiff backing comprises an attaching flap which is fixed in position, an envelope body hingedly connected to the flap along a fold line, and a photograph independently hinged to the flap and desirably adapted to be turned about the same 50 fold line as the envelope body. Since the envelope and the photograph can be turned up independently or together, it is apparent that the photograph may be turned up to expose the en-

velope or that both the photograph and the envelope may be turned up to expose an underlying photograph. The successive photograph and envelope units may, therefore, be arranged in overlapping or stepped relation in the book, 5 folder or upon any comparatively stiff backing, and they are desirably so arranged in order to provide a compact record.

There is no danger of the negative or any other material contained in the envelope being 10 lost from the envelope because the picture, in the normal position, extends down across the insertion opening of the envelope and covers and guards such opening.

Other objects and advantages will hereinafter 15 appear.

In the drawings forming part of this specification and disclosing certain preferred embodiments of the invention:

Fig. 1 is a plan view of an open album showing 20 two adjacent pages completely filled, several of the photograph and envelope units on the right hand page being turned upward;

Fig. 2 is a view similar to Fig. 1 but different from Fig. 1 in that the lowermost of the envelopes shown turned up in Fig. 1 is shown in its normal or downturned position in Fig. 2;

Fig. 3 is a plan view of an envelope of the kind employed in Figs. 1 and 2;

Fig. 4 is a view in section of the envelope of 30 Fig. 3;

Fig. 5 is a view similar to Fig. 4 showing an envelope like that of Fig. 4, but in which the adhesive is applied to the back instead of the front of the attaching flap;

Fig. 6 is a fragmentary view generally similar 35 to Fig. 2, but showing the envelope of Fig. 5 employed in place of the envelope of Fig. 4;

Fig. 7 is a fragmentary view generally similar to Fig. 1, but showing the envelope of Fig. 5 40 employed in place of the envelope of Fig. 4;

Fig. 8 is a view showing a modified form of 45 album and envelope intended to be used when miniature film is employed;

Fig. 9 is a fragmentary view of an envelope 50 similar to the envelope of Fig. 4 but having a modified hinge and attaching flap construction;

Fig. 10 is a fragmentary view of a picture and envelope assembly in which the envelope flap is designed to provide hinges for a series of 55 photographs arranged in stepped relation;

Fig. 11 is a fragmentary view in section taken on the line 11—11 of Fig. 10 looking in the direction of the arrows and showing the envelope and several pictures extended out at an angle 55

from the backing sheet for clearness of illustration, and

Fig. 12 is a fragmentary view of the assembly of Figs. 10 and 11 showing one of the pictures turned upward.

In the form of the invention illustrated in Figs. 1 to 4 disclosure is made of a folder or album consisting of a front 2 and a back 3 hingedly connected to one another. The flexible, intermediate portion 4 connecting the front and back may have additional stiff sheets pasted or otherwise secured to it. The ordinary loose leaf ring binder may be employed if desired, but the sheets used are desirably of stiff paper or of cardboard capable of carrying a considerable number of the envelopes and photographs.

On the front and back 2 and 3 of the folder shown in Fig. 1 a number of photograph and envelope units are attached. The envelope forming a part of one of these units is best seen in Figs. 3 and 4. The envelope comprises front and back body portions 5 and 6 which are folded into superposed relation in the usual way. The body portion 5 has side flaps 7 (see Fig. 1) which are folded over against the outer face of the body portion 6 and adhesively united to the latter. The details of the envelope body construction are unimportant, however, and may be varied as desired, so long as an envelope having a body and a free flap is provided. The body portion 6 is provided with an integral flap 8 which extends above the body portion 5 and which is divided from the body portion 6 by a fold line 9. The entire area of the outer or rear face of the flap 8 is coated with adhesive 10. Tabs 11 are cut from the flap 8. These tabs are shown as being in the form of isosceles trapezoids, although they may take various other shapes. Each of these tabs as shown is completely severed along the two sides and the shorter base. The longer base of each tab desirably coincides with the fold line 9 and is preferably cut through along a portion of its length to provide a slit 12 extending part way across the longer base. The slit 12, however, is spaced inward substantially from the extremities of the longer base of the tab. The slits serve to define the fold line of the tabs accurately and sharply. The face of the body portion 5 is printed with lines for the writing in of data and with suitable legends such as "Date", "Location", "General Remarks" and "Title", for facilitating the entry of desired information concerning the photograph with which the envelope is to be associated. The tabs 11, two or more, are utilized for the attachment to the envelope of a photograph 13. Such attachment may conveniently be effected with the envelope in a position like that shown in Fig. 3 by bending the tabs 11 upward out of the plane of the flap 8, moistening them, and thrusting the photograph into the angle between the flap and tabs until it is arrested by the junction of the flap and tabs. The moistened tabs are then pressed down against the back of the photograph to unite the tabs firmly to the photograph. The photograph is in this way hingedly connected to the flap 8 and to the envelope body, each of the three elements 13, 10 and 5-6 being free to turn about the fold line 9 relative to the other two. The negative from which the photograph has been made is inserted in the envelope and the unit is attached in the album by moistening the adhesive on the flap 8 and pressing the flap in proper position 75 in the album. The picture normally extends

downward from the attached flap and completely covers and conceals the envelope. When it is desired to consult the data on the face of the envelope the picture may be turned up to expose the envelope, and when the picture is in this position the negative may be extracted from the envelope if desired.

Another way of effecting the same combination of envelope, picture and album which may be practised, if desired, is to attach the envelope 10 or a series of envelopes in the album before attaching the pictures. Care should be taken in such case not to moisten the gum on the tabs, so as to leave the tabs free to be turned upward and to have the pictures attached to them. The 15 negatives can, of course, be inserted in the envelopes after the assembly in the album is complete if desired.

The envelopes can be associated with the album sheets with sufficient space between them to enable the pictures to stand entirely clear of one another so that all the pictures on a sheet are fully exposed to view. A more compact arrangement, and one which is regarded as preferable for most purposes, is that illustrated in Figs. 1 25 and 2 wherein the gummed flaps stand substantially edge to edge and each photograph covers all but the lower margin of the next photograph beneath it. This enables a very considerable number of the photograph and envelope units 30 to be attached upon a single sheet of the album.

The envelope of Fig. 5 is very similar to that of Fig. 4, and may differ only in the fact that the adhesive 10a is applied upon the opposite face of the flap 8a from that upon which the 35 adhesive 10 is applied to the flap 8. The side flaps may be provided on either body portion of the envelope, but as shown the arrangement is the same as that of Figs. 1 to 4. Although the envelope is constructed in exactly the same 40 way as the envelope of Fig. 4, the body portion 5a now becomes the back of the envelope and the body portion 6a becomes the front, so that the printed form for facilitating the entry of data is printed upon the face of the body portion 6a. An album 1a is illustrated in Figs. 6 and 7 as having envelopes of the type shown in Fig. 5 attached in it. As before, the flaps 8a are attached to the album sheet, and the tabs 11a folded on line 12a are utilized as hinges for 50 the attachment of photographs. The only difference resulting from the modification of the envelope from the form of Fig. 4 to that of Fig. 5 is that the insertion opening is now at the back of the envelope instead of at the front of it. 55 This simply requires that the envelope be turned up to the position illustrated in Fig. 7 in order to expose the insertion opening and permit a negative of the photograph to be inserted or withdrawn.

In the form of the invention shown in Fig. 8 the album and the envelope structure have been modified in order to provide for keeping miniature film in a small envelope which substantially fits the film. A sheet 2b of the album has attached to it a sheet of flexible fabric 14. The fabric 14 is adhesively united to the sheet 2b in the zones or stripes 15, but intervening zones or stripes 16 are kept dry so as not to adhere to the album sheet. The intervening zones 16 are, 65 however, coated with adhesive and these zones are cut so as to form series of photograph attaching and envelope attaching hinges. The hinges are provided by forming angular cuts 17, one above the other, throughout the height of 70 75 75

each zone 16. Each attaching tab is triangular in form. It may be a hollow triangle since the apex of one tab may extend into the body of the next tab above it. The statement that the entire zone 16 is kept dry and unadhered is not quite accurate, since the small areas lying outside the hinge triangles but within the zone are desirably, though not necessarily, pasted down. For attaching a tier of pictures a width of the sheet 10 comprising three of the zones 16 is utilized. The picture has its upper rear margin adhesively united to a pair of correspondingly located hinges 18 lying in the two outer zones of the set of three. A small envelope 19 has its back 6b adhesively united to the corresponding hinge of the intervening hinge zone. The envelope 19 may be exactly like the envelope of Fig. 4 with the exception that it is a smaller envelope and that it has no tabs punched from its flap portion. It 20 does have a flap portion, however, which is gummed on its outer face, and this flap portion is adhesively united to the back of the photograph so that the envelope itself forms a connecting link between the photograph and the intermediate hinge member of the album to provide a third hinge for the photograph. As before, both the envelope and the photograph are free to hinge relative to the album sheet and relative to one another. The insertion opening of the 30 envelope is exposed by turning the photograph upward while leaving the envelope turned downward.

The envelope of Fig. 9 is generally similar to the envelope of Fig. 4. In this instance, however, the body of the envelope is provided beyond the insertion opening with hinges 25 and with tabs 26 cut from within the hinges. This envelope is designed to be used by pasting the tabs 26 as well as the main part of the flap 24 to the support or backing sheet, such as a sheet 40 of an album, and by pasting the hinges 25 to the back of the photograph. The hinges and tabs which are folded on fold line 23 and the flap 24 are all gummed on the same side, but this may be either the side toward the insertion opening 45 or the side away from the insertion opening as desired.

In the form of the invention shown in Figs. 10 to 12 disclosure is made of an envelope 38 having a flap 31 designed to be pasted upon a supporting sheet 32 and formed to provide a plurality of sets of hinges so that several photographs 33, 34, 35 can be mounted in stepped relation upon the flap of a single envelope. The flap may, 50 of course, be of any length desired and may extend through the entire height of the supporting sheet so that only one envelope 38 is provided on a sheet for holding the film for all of the pictures on that sheet. The hinges 36 are formed from 55 the flap portion of the envelope by angular cuts, the vertex of each hinge extending into the body of the hinge next above it. The hinges are arranged in vertical zones, and a set of hinges for mounting a photograph consist of one hinge of 60 each zone, the hinges of the set being all disposed in horizontal alignment. This form of the invention is particularly desirable where film is used which is so small that the film frames cannot be conveniently handled as individual 65 units. In this form of the invention either face of the combined hinge and flap structure may be selected for coating with adhesive.

While I have illustrated and described in detail certain preferred forms of my invention, it 70 is to be understood that changes may be made

therein and the invention embodied in other structures. I do not, therefore, desire to limit myself to the specific constructions illustrated, but intend to cover my invention broadly in whatever form its principle may be utilized.

In the appended claims the terms "album" and "photograph" are used broadly and illustratively rather than literally, the former to comprehend any comparatively stiff backing sheet or sheets whether in folder or book form or otherwise, and 10 the latter to comprehend any cards, slips or other units which might desirably be hingedly mounted upon a support.

I claim:

1. An envelope adapted for use in photograph 15 albums comprising a body having an insertion opening and including front and back portions, a gummed attaching flap integral with one of said body portions and divided from the body portion by a fold line, and gummed foldable tabs 20 formed from portions of said flap to constitute picture attaching hinges.

2. An envelope as set forth in claim 1 wherein in the flap is gummed on its face which is opposite to or remote from the insertion opening. 25

3. An envelope as set forth in claim 1 wherein in the flap is gummed on its face which is toward or adjacent to the insertion opening.

4. An envelope as set forth in claim 1 wherein the tabs are divided from the envelope body 30 along the same fold line which divides the flap from the envelope body.

5. An envelope adapted for use in a photograph album comprising a body having an insertion opening and including front and back portions 35 and a gummed extension on one of the body portions adjacent the position of attachment for hingedly attaching the envelope in an album, and other gummed extensions on the same body portion for hingedly connecting a 40 photograph to the envelope body.

6. A photograph and envelope unit adapted for attachment in an album or upon any comparatively stiff backing, comprising an envelope body, a gummed attaching flap divided from the body 45 by a fold line, gummed photograph hinges integral with the envelope and foldable independently of the body and the flap, and a photograph attached to said hinges.

7. A photograph and envelope unit adapted for attachment in an album or any comparatively 50 stiff backing, comprising an envelope body composed of front and back portions which jointly define an enclosure receiving compartment entered through an insertion opening, an attaching flap integral with one of said body portions and divided from such body portion by a fold line, hinge tabs also integral with the envelope body and foldable independently of the body and the flap, and a photograph attached to said hinge 55 tabs in a position to cover and guard the insertion opening.

8. A photograph and envelope unit adapted for attachment in an album or upon any comparatively stiff backing, comprising an envelope body 65 composed of front and back portions for jointly defining an enclosure receiving compartment entered through an insertion opening, an attaching flap integral with the front body portion and adapted to be pasted in an album to locate the 70 insertion opening toward the album sheet to which the flap is attached and just below the attached flap, photograph hinges also integral with the front body portion and foldable relative to said flap and body portion, and a photograph 75

attached to said hinges in position to overlie the envelope.

9. A photograph album comprising a supporting sheet and a series of attached envelopes, each envelope including an attaching flap whereby it is hingedly attached to the supporting sheet, and photograph hinges for independently hingedly connecting a photograph to the envelope.

10. A photograph album comprising a supporting sheet, an envelope having a body portion and a foldable gummed extension divided from the body portion by a fold line, a photograph adhesively united with the extension, and means adhesively connected to the supporting sheet for hingedly connecting the photograph and the envelope body to the supporting sheet, each with capacity to be individually swung away from the supporting sheet.

11. A photograph album comprising a supporting sheet, vertically arranged series of hinges attached to the sheet, said hinges being disposed in horizontally aligned sets, a photograph attached directly to the two outer hinges of a set, and an envelope having a body portion attached to an intermediate hinge of the set, and a foldable flap attached to the back of the photograph, said envelope constituting a connection between the intermediate hinge and the photograph.

12. A photograph album comprising a supporting sheet, a series of horizontally aligned hinges carried by the sheet and foldable relative to the sheet, a small envelope having a body portion attached to an intermediate hinge of said series and having a gummed flap disposed, when the envelope is attached to the hinge, so that it lies in transverse alignment with the other hinges of

the set and a photograph marginally attached to said other hinges and to the envelope flap.

13. An envelope adapted for use in an album comprising a body having an insertion opening and including front and back portions, a gummed flap integral with a body portion and divided therefrom by a fold line, and a plurality of sets of hinges formed from the material of the flap for hingedly mounting photographs in stepped relation.

14. A photograph album comprising a supporting sheet, a vertically arranged series of hinges attached to the sheet, said hinges being disposed in horizontally aligned sets, photographs attached each to a horizontally aligned set of hinges with the capacity to be individually swung away from the supporting sheet, and envelopes for containing photographic negatives, interspersed between certain of the photographs, and also having the capacity to be individually swung away from the supporting sheet.

15. A photograph album comprising a supporting sheet, an envelope having its body hingedly connected to the sheet, and means for attaching photographs or like articles in stepped overlapping relation to the supporting sheet for hinging movement relative to the sheet and independently of the envelope body, but in such relation that the envelope body is covered and concealed by one or more of the photographs but may be uncovered for access by the hinging movement of the adjacent photograph away from the sheet.

ALBERT A. AINSWORTH. 35
